KEY HOLDER

Arthur H. Boys, New York, N.Y., assignor to Ottavia Incorporated, New York, N.Y., a corporation of New York

Application December 5, 1957, Serial No. 48,792

Term of patent 14 years

(Cl. D17—14)

Fig. 1 is a front view of a key holder showing my new design;

Fig. 2 is a rear view thereof, the broken line illustration of the key chain having been eliminated for convenience of illustration; and

Fig. 3 is a top view thereof.

The essential features of the design reside in the portions shown in solid lines in the drawing.

I claim:

The ornamental design for a key holder, substantially as shown and described.
